UNITED STATES PATENT OFFICE.

LOUIS N. D. WILLIAMS, OF OGONTZ, PENNSYLVANIA.

STITCH-CHAIN-FORMING MACHINE.

1,127,338.

Specification of Letters Patent. Patented Feb. 2, 1915.

Application filed November 14, 1913. Serial No. 800,948.

To all whom it may concern:

Be it known that I, LOUIS N. D. WILLIAMS, a citizen of the United States, residing in Ogontz, Pennsylvania, have invented certain Improvements in Stitch-Chain-Forming Machines, of which the following is a specification.

My invention consists of a machine for forming a course of stitches for subsequent application to the points or quills of a transfer device whereby they may be applied to the needles of a knitting machine, the object of my invention being to facilitate the application of the stitches to the points of the transfer ring and to insure the accuracy of such transfer.

In the accompanying drawing—Figure 1 is a view, partly in vertical section and partly in side elevation, of a machine constructed in accordance with my invention; Fig. 2 is a plan or top view of the same; Fig. 3 is a vertical sectional view of sufficient detail of the machine to illustrate the application thereto of the points of the transfer ring; Fig. 4 is a plan view of part of the stitch carrying ring with the stitches thereon; Fig. 5 is a side view of one of the cams of the machine, and Fig. 6 is a view illustrating a modification of one of the elements of the machine.

In the drawing I have illustrated my invention as applied to a machine for forming a circular course of stitches for use in connection with a circular knitting machine, but the invention is also applicable to machines for the formation of a straight row of stitches for application to the needles of a straight knitting machine.

In the drawing, 1 represents a fixed structure suitably mounted upon a table or bench and having a ring 2 in which is mounted so as to be free to rotate the hub 3 of an annular disk 4, from which project upwardly two annularly disposed sets of pins 5 and 6, one outside of the other, the pins of one set being separated from those of the other set to an extent dependent upon the size of the stitch to be produced (see Fig. 2). In Fig. 1 of the drawing I have for convenience only illustrated the diametrically opposite pairs of pins.

The periphery of the disk 4 has formed upon it ratchet teeth 7 with which engages a spring pressed pawl 8 pivotally mounted upon a sliding bar 9 suitably guided in a bearing 10 on the frame 1 and having re-

ciprocating movement imparted to it at suitable intervals by any appropriate means, such for instance as a lever 11 pivotally mounted upon a fixed pin 12 on the frame 1 and slotted for engagement with a projecting pin 12^a on the bar 9, as shown in Fig. 1. The lever 11 is acted upon by a cam 13 on the shaft 14 to which rotary movement in the direction of the arrow 65 Fig. 1 is imparted in any desired manner, said cam acting upon a projection 15 on the lever and said projection being maintained in contact with the cam by means of a spring 16 connected at one end to the lever 11 and at the other end to a suitable fixed point of engagement on the frame 1.

Any suitable stitch forming device and yarn guide may coöperate with the pairs of pins 5 and 6 to form stitches each containing 75 a pair of said pins. In the present instance I have shown for this purpose a latch needle 17 mounted so as to be free to reciprocate in a bearing 18 on the frame 1, the butt 19 of said needle being engaged by a pair of pins 20 projecting laterally from the upper portion of a lever 21 which is pivotally mounted upon the pin 12 and is acted upon by a cam 22 on the shaft 14, a projection 23 on said lever 21 being maintained in contact with said cam 22 by means of a spring 24. The cams 13 and 22 are so timed that intermittent movements of partial rotation, in the direction of the arrow Fig. 2, and to the extent of one tooth of the ratchet wheel 90 7, will be imparted to the disk 4 when the needle 17 occupies the retracted position shown in Fig. 1, the disk 4 being at other times quiescent.

Depending from the ring 3 is a bracket 95 25 which extends beneath said ring and has disposed in line with the axis thereof a bearing 26 in which is mounted so as to be free to rotate a tubular shaft 27 supported vertically in said bearing in any suitable way, as for instance by means of a collar 28 on the shaft resting upon the top of said bearing, as shown in Fig. 1. The shaft 27 has at the top an arm 29 with thread guiding eye 30 and said shaft 27 has, at its lower end, an arm 31 100 105 whose outer end carries an anti-friction roller acted upon by a side-facing cam 32 on the shaft 14, a spring 33 serving to connect a pin 34 on the arm 31 and a pin 35 on the frame 1, so as to maintain said roller 110 constantly in contact with the face of the cam 32, as shown in Fig. 5.

The parts are so timed that the movements of the disk 4 will take place between the reciprocations of the needle 17 and while the said needle is in the retracted position shown in Fig. 1, the movements of the needle taking place between the intermittent movements of the ring 4 so that said needle will be projected between the pairs of pins 5 and 6 in succession; the thread feeding arm 29 moving so as to lay its thread across the needle 17 when the latter is in the projected position. The result of this operation is to form a succession of stitches each containing a pair of pins 5 and 6, as shown in Fig. 4, and when the circle of stitches is completed the points of the transfer ring can be applied to the pins 5 and 6, as shown in Fig. 3, each point 36 of the transfer ring occupying a position between the pins of a pair, and the course of stitches can then be transferred from the pins 5 and 6 to the points of the transfer ring by raising a stripper 37 which normally occupies a position at the bases of the pins, as shown in Figs. 1 and 3.

In a machine intended for the formation of a straight row of stitches a straight pin-carrying bar will take the place of the disk 4 and said bar will have intermittent longitudinal movements instead of intermittent movements of partial rotation. Tubes, such for instance as shown in Fig. 6, may, if desired, replace the pairs of pins but the use of the latter is preferred.

I claim:

1. In a stitch chaining machine, the combination of stitch forming mechanism with a carrier having a plurality of stitch receivers each constructed for the reception of a point of a transfer device, means for intermittently operating said stitch forming mechanism, and means for changing the relation of the stitch receivers and stitch forming mechanism in the intervals between the operations of the latter, whereby stitches may be formed around the stitch receivers in succession.

2. The combination, in a stitch chaining machine, of stitch forming mechanism, a carrier having a plurality of stitch receiv-

ers each consisting of a pair of projecting pins separated from one another in the direction of travel of the stitch forming needle, means for intermittently operating said stitch forming mechanism, and means for changing the relation of the stitch receivers and stitch forming mechanism in the intervals between the operations of the latter.

3. The combination, in a stitch chaining machine, of a rotatable disk carrying a plurality of stitch receivers each adapted for the reception of a point of a transfer device, stitch forming mechanism, means for intermittently operating the latter, and means for imparting intermittent movements of partial rotation to the stitch receiver ring in the intervals between the operation of the stitch forming mechanism.

4. The combination, in a stitch chaining machine, of stitch forming mechanism, a rotatable carrier having a circularly disposed series of stitch receivers each comprising a pair of projecting pins separated from one another in the direction of travel of the stitch forming needle, means for intermittently operating said stitch forming mechanism, and means for imparting intermittent movements of partial rotation to said stitch receiver ring in the intervals between the successive movements of the stitch forming mechanism.

5. In a stitch chaining machine, the combination of a reciprocating needle, and a vibrating yarn guide, with a carrier having a plurality of stitch receivers each constructed for the reception of a point of a transfer device, means for reciprocating said needle and vibrating said yarn guide, and means for changing the relations of the stitch receivers and needle in the intervals between the reciprocations of the latter.

In testimony whereof, I have signed my name to this specification, in the presence of two subscribing witnesses.

LOUIS N. D. WILLIAMS.
